UNITED STATES PATENT OFFICE

168,930

COMBINED CIGARETTE AND GOLF TEE HOLDER

Walter E. Freeman, Augusta, Ga.

Application September 11, 1952, Serial No. 21,420

Term of patent 7 years

(Cl. D85—8)

To all whom it may concern:

Be it known that I, Walter E. Freeman, a citizen of the United States, residing at Augusta, in the county of Richmond and State of Georgia, have invented a new, original, and ornamental Design for a Combined Cigarette and Golf Tee Holder, of which the following is a specification, reference being had to the accompanying drawing, forming part thereof.

Figure 1 is a perspective view of a combined cigarette and golf tee holder, showing my new design, and

I claim:

The ornamental design for a combined cigarette and golf tee holder, as shown.

WALTER E. FREEMAN.
